UNITED STATES PATENT OFFICE.

BENJAMIN H. COOPER, OF DENVER, COLORADO.

DESIGN FOR A COMBINATION-TOOL.

50,015.

Specification for Design.

Patented Dec. 12, 1916.

Application filed January 28, 1916. Serial No. 74,888. Term of patent 14 years.

To all whom it may concern:

Be it known that I, BENJAMIN H. COOPER, a citizen of the United States, residing at Denver, in the county of Denver and State of Colorado, have invented a new, original, and ornamental Design for a Combination-Tool, of which the following is a specification, reference being had to the accompanying drawing, forming a part thereof.

The figure is a perspective view of a combination tool, showing my new design.

I claim:

The ornamental design for a combination tool, as shown.

BENJAMIN H. COOPER.

Witnesses:

PAUL W. DE FOE,
G. G. EARLE.
